ATTORNEY

UNITED STATES PATENT OFFICE.

JOHN E. JOHNSON, OF LEWISBURG, WEST VIRGINIA.

DESIGN FOR A POISON-BOTTLE.

50,421.

Specification for Design.

Patented Mar. 6, 1917.

Application filed December 19, 1916. Serial No. 137,906. Term of patent 14 years.

To all whom it may concern:

Be it known that I, JOHN E. JOHNSON, a citizen of the United States, residing at Lewisburg, in the county of Greenbrier and State of West Virginia, have invented a new, original, and ornamental Design for Poison-Bottles, of which the following is a specification, reference being had to the accompanying drawing, forming a part thereof.

The figure is an elevation of a poison bottle showing my new design.

I claim:

The ornamental design for a poison bottle, as shown.

JOHN E. JOHNSON.

Witnesses:

P. C. HOGSEN,
JNO. S. CRAWFORD.
